UNITED STATES PATENT OFFICE

2,214,313

ADJUSTABLE ANGLE CONVEYER SECTION

Edwin Lloyd Swanson, Dines, Wyo.

Application June 9, 1939, Serial No. 278,350

3 Claims. (Cl. 198—220)

This invention relates to a conveyer section for reciprocating conveyers for conveying coal and other material from one point to another, the general object of the invention being to provide pan sections attached to carriages, the wheels of which engage adjustable track sections which cause the pan sections to assume an angle or curve according to the adjustment of the track sections.

10 Another object of the invention is to arrange the device on posts with means for adjusting the elevation of the device from the surface.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which—

Figure 1 is a top plan view of the invention with parts broken away.

Figure 2 is an elevation thereof.

Figure 3 is a top plan view with all the parts removed excepting the track carrying part on the main base or frame.

30 Figure 4 is a perspective view of part of the carriage construction.

Figure 5 is a section on the line 5—5 of Figure 3.

In these drawings the numeral 1 indicates the main frame or base which is supported on the uprights 2 in an adjustable manner by means of the cup-shaped members 3, one of which is slidably arranged on each post and receives the wedges 4 which are pressed into the member 3 by the flanged collar 5 surrounding the post and fastened to a flange of member 3 by the bolts 6. Thus by tightening the bolts 6 the wedges are forced into the member 3 to adjustably hold the members 3 and the parts associated therewith on the post. It will be understood that by loosening the bolts 6 the wedges will be released so that the member 3 can be adjusted vertically on each post. A bolt 7 extends from each member 3 and passes through a hole in a depending flange 1' of the member 1, this connection enabling the member 1 to be placed at an angle or inclination with respect to the posts. Adjustable brace bars 8 connect lower portions of the posts with underparts of the member 1 as shown more particularly in Figure 2.

A pair of track carrying members or sub-bases 9 are adjustably arranged on the base 1 by being pivoted thereto as at 10 at one corner of each sub-base with bolts 11 passing through arcuate slots 12 in the base 1. Thus by loosening the bolts 11 each sub-base or track carrying section 9 can be adjusted about the pivot 10 and then by tightening the bolts the sub-base will be held in adjusted position.

Each sub-base or track carrying section has a 10 flanged outer rail 13, and a pair of flanged rails 14 which are placed relatively close together with the flanges extending toward each other.

A middle carriage section is shown at 15 and has the rollers 16 at its ends for engaging intermediate parts of the main frame 1 and this carriage section is formed with a bar 17 to which the forked part 18 of a bar 19 of a carriage section 20 is pivoted as at 21. A horizontally arranged roller 22 is carried by the pivot 21. 20 This section 20 is of substantially triangular shape and carries a vertical roller 23 at its small end. A carriage section 24 formed on a bar with its ends turned downwardly to carry the vertical rollers 25 is pivoted adjacent one end to the 25 outer end of the bar 19 as shown at 26, and a horizontal roller 22 is carried by the pivot 26. As will be seen from Figure 1 a carriage section similar to that shown at 20 is connected to the left hand end of the section 15 and a carriage section similar to that shown at 24 is connected to the left hand end of this second carriage section 20. A long centrally arranged pan section 27 is fastened to the carriage section 15 by bolts 28 and a shorter pan section 29 is connected 35 to each of the carriage sections 20 while shorter end pan sections 30 are fastened to the two carriage sections 24 by a horizontally arranged pin 31 passing through ears 32 projecting from the section 24, this arrangement permitting the outer pan section to swing up and down. As shown in Figure 1 the pan sections are provided with wide ends 33 for receiving the ends of the adjacent sections so as to permit free movement of the inner pans.

45 The posts 2 are preferably in the form of screw jacks so that they can be shortened and lengthened to properly engage the floor and ceiling of a mine and it will be seen that the track sections or short bases can be adjusted to have the pan sections form different arcs or angles according to the turn the conveyer is to make.

The wheel 23 of each carriage 20 engages under the flange of the rail 13 while the outer wheel 25 of each carriage section 24 engages the flat 55

part of each member 9 inwardly of the rail 13 and the horizontal wheels or rollers 22 of each carriage 20 engage the rails 14 under the flange thereof with the other wheel 25 of the carriage 5 section 24 engaging the member 9 outwardly of the outer rail 14 as shown in Figure 1. The straight portions or main conveyer portions are connected with the pan sections 30 so that as a main conveyer section is reciprocated this reciprocatory movement is communicated to the parts forming the invention.

By this invention the coal or other material is conveyed from a main conveyer section to another section which lies at an angle to the first section. There is no lost motion in the stroke of the driven pan line. A much longer pan line can be driven with this arrangement than can by the arrangements now in use.

It is thought from the foregoing description 20 that the advantages and novel features of the invention will be readily apparent.

It is to be understood that changes may be made in the construction and in the combination and arrangement of the several parts provided that such changes fall within the scope of the appended claims.

Having described the invention, what is claimed as new is:

1. A conveyer device of the class described comprising a main frame, track carrying members pivoted to the frame for adjustment to different angles, means for holding said members in adjusted position, track forming rails carried by said members, carriage sections pivotally connected together and having wheels engaging the track forming members and pan sections fastened to the carriage sections.
2. A conveyer device of the class described comprising a main frame, track carrying members pivoted to the frame for adjustment to different angles, means for holding said members in adjusted position, track forming rails carried by said members, carriage sections pivotally connected together and having wheels engaging the track forming members and pan sections fastened to the carriage sections, posts and means for adjustably supporting the main frame from said posts.
3. A conveyer device of the class described comprising a main frame, track carrying members pivoted to the frame for adjustment to different angles, means for holding said members in adjusted position, track forming rails carried by said members, carriage sections pivotally connected together and having wheels engaging the track forming members and pan sections fastened to the carriage sections, the outer pan sections being pivotally connected with their carriage sections to swing about horizontal axis.

EDWIN LLOYD SWANSON.
